CLAIM

The ornamental design for a side cabinet for medical/dental operatory, as shown and described.

DESCRIPTION

FIG. 1 is a front, side perspective view of a first embodiment of the side cabinet for medical/dental operatory;

FIG. 2 is a front elevational view thereof;

FIG. 3 is a right side elevational view thereof;

FIG. 4 is a left side elevational view thereof;

FIG. 5 is a top plan view thereof; and,

FIG. 6 is a front, side perspective view of a second embodiment of the side cabinet for medical/dental operatory.

The broken lines shown in the drawings are for illustrative purposes only and form no part of the claimed design.
